DESIGN FOR A WRIST WATCH BRACELET

Matthew Marcus, Nassau, Bahamas, assignor of
one-half to George Curtis Johnson, Nassau,
Bahamas

Application December 3, 1948, Serial No. 149,969

Term of patent 14 years

(Cl. D45—4)

To all whom it may concern:

Be it known that I, Matthew Marcus, a citizen
of the Bahamas, residing at Nassau, Bahamas,
have invented a new, original, and ornamental
Design for Wrist Watch Bracelet, of which the
following is a specification, reference being had
to the accompanying drawing, forming a part
thereof.

Fig. 1 is an edge view of a wrist watch bracelet
embodiment my new design;

Fig. 2 is a plan view of the parts of the wrist
watch bracelet in separated position and showing
the outer side thereof as seen in Fig. 1;

Fig. 3 is a plan view of the parts of the wrist
watch bracelet in separated position and showing
the inner side thereof as seen in Fig. 1; and,

Fig. 4 is a top plan view of a wrist watch bracelet
corresponding to Fig. 1.

I claim:

The ornamental design for a wrist watch bracelet,
as shown.

MATTHEW MARCUS.
